DESIGN FOR A HANDBAG

Morris White, New York, N. Y.

Application April 4, 1936, Serial No. 61,942

Term of patent 14 years

To all whom it may concern:

Be it known that I, Morris White, a citizen of the United States, residing at New York, in the county of New York and the State of New York, have invented a new, original, and ornamental Design for a Handbag, of which the following is a specification, reference being had to the accompanying drawing, forming part thereof.

Fig. 1 is a side elevation of the handbag, showing my new design.

Fig. 2 is an end view.

Fig. 3 is a top plan view thereof.

In Figures 1 and 2 the handle portion is shown broken away for convenience of illustration.

The dominant feature of my design resides in the handle member comprising the strap attached to one side of the handbag and the ornamental loop through which the strap extends, which is attached to the other side of the handbag.

I claim:

The ornamental design for a handbag, substantially as shown and described.

MORRIS WHITE.
